(57) **CLAIM**

The ornamental design for a flameless electric lighter, as shown and described.

DESCRIPTION

FIG. 1 is a perspective view of a flameless electric lighter showing my new design in the “off” position.

FIG. 2 is a perspective view of a flameless electric lighter showing my new design in the “on” position with dual heat beams in an “X” configuration.

FIG. 3 is a front view of a flameless electric lighter showing my new design in the “off” position.

FIG. 4 is a front view of a flameless electric lighter showing my new design in the “on” position with dual heat beams in an “X” configuration.

FIG. 5 is a rear view of a flameless electric lighter showing my new design in the “off” position.

FIG. 6 is a rear view of a flameless electric lighter showing my new design in the “on” position with dual heat beams in an “X” configuration.

FIG. 7 is a right-side view of a flameless electric lighter showing my new design in the “off” position.

FIG. 8 is a right-side view of a flameless electric lighter showing my new design in the “on” position with dual heat beams in an “X” configuration.

FIG. 9 is a left-side view of a flameless electric lighter showing my new design in the “off” position.

FIG. 10 is a left-side view of a flameless electric lighter showing my new design in the “on” position with dual heat beams in an “X” configuration.

FIG. 11 is a top view of a flameless electric lighter showing my new design in the “off” position.

FIG. 12 is a top view of a flameless electric lighter showing my new design in the “on” position with dual heat beams in an “X” configuration; and,

FIG. 13 is a bottom view of a flameless electric lighter showing my new design.
